UNITED STATES PATENT OFFICE.

ROY HENDERSON, OF COLUMBUS, GEORGIA.

CUT-OUT FUSE.

Application filed July 12, 1922. Serial No. 574,466.

To all whom it may concern:

Be it known that I, Roy HENDERSON, a citizen of the United States, residing at Columbus, in the county of Muscogee and 5 State of Georgia, have invented new and useful Improvements in Cut-Out Fuses, of which the following is a specification.

This invention relates to fuse devices for interposition in an electric circuit and has 10 for its object the provision of a novel cut out fuse and lightning arrester designed to be used in connection with transformers, an important object being the provision of a rotatable carrier having a series of fuse 15 wires mounted thereon, the carrier being rotatable to throw a selected one of the fuses into the circuit whenever one burns out.

Another object is the provision of a device of this character which is provided internally with a lightning arrester which is 20 in circuit with the fuse, the device also including a knife switch for breaking the circuit when desired.

Another object is the provision of a device of this character in which the fuse carrier may be rotated from the outside of the casing or box without necessitating opening the front thereof.

An additional object is the provision of a 25 device of this character which will be simple and inexpensive in manufacture, easy to install, convenient in use and a general improvement in the art.

With the above and other objects and advantages in view the invention consists in the details of construction to be hereinafter more fully described and claimed and illustrated in the accompanying drawings in which:

40 Figure 1 is a perspective view of the device in closed position,

Figure 2 is a front elevation thereof with the door in open position,

Figure 3 is a vertical section taken 45 through the lightning arrester,

Figure 4 is a vertical section taken through the fuse carrier,

Figure 5 is a horizontal sectional view on the line 5—5 of Figure 2,

50 Figure 6 is a detail cross section on the line 6—6 of Figure 2,

Figure 7 is a horizontal section taken on the line 7—7 of Figure 2.

Figure 8 is a bottom plan view.

55 Referring more particularly to the drawings the numeral 10 designates a rectangular

box or casing which is provided at its front with an upwardly swinging hinged door 11 which may include a glass pane 12 through which inspection may be made of the interior. This door is provided with a brace 13 which operates to limit its swinging movement and to hold it in open position when desired. Secured upon the inner face of the door are clips 14 for holding a switch 60 throwing stick for a purpose to be herein-after explained. Any suitable brackets are provided on the box or casing so that it may be mounted at the desired location.

65 Located within the casing is a vertical partition 18 and a horizontal partition 19 which operate to define a compartment 20 within which is located the fuse mechanism to be described. Located above the partition 19 is a knife switch 21 which has a swingable blade provided with a handle 22 formed with a hole 23 within which may be engaged the hook 16 on the stick 15 for the purpose of moving the switch handle. Located against the back of the casing 70 between one side thereof and the partition 18 is a lightning arrester 24 designed to carry a current of approximately 2300 volts. Extending through the bottom of the casing is an insulator 25 through which passes a wire 26 which is connected with one end of the lightning arrester and which has its other end connected with a suitable ground clamp for the lightning arrester. Extending 75 through one side of the casing is an insulator 28 through which extends one of the line wires 29 which is connected with one terminal of the switch 21 which has its other terminal connected with the other terminal of the lightning arrester by a wire 30. 80

85 Mounted within the compartment 20 are upper and lower bearings 31 through which is journaled a shaft 32 which extends through the bottom of the casing and which has its lower end carrying a handle disk 33 90 provided with graduations 34 designed to register with an index mark 35 on the bottom of the casing. Mounted upon this shaft between the bearings 31 is a cylinder 36 of porcelain which is formed with a plurality of grooves 37. Mounted upon the reduced ends of this cylinder are metal strips 38 which carry binding screws 39 to which are connected the ends of fuse wires 40 which lie within the grooves 37 and which are easily 95 renewable when burnt out.

100 Secured upon the back wall of the casing

is a supporting block 41 upon which is mounted a leaf spring 42 which bears against the cylinder for preventing it from having too free rotation when turned by means of the handle 33.

Mounted on the back of the casing are supports upon which are mounted metallic members 44 provided with binding posts 45 and 46. The post 45 has a wire 47 connected therewith which leads out through an insulator 48 in the side of the casing to the primary of the transformer not shown. Connected with the post 46 is a wire 49 which is connected with the knife switch as shown. The wires 29 and 47 are of course connected with the line wires of the current supply. Carried by the metallic members 44 are spring contacts 50 which bear against the metal strips 38 at the top and bottom of the cylinder.

In the use of the device it will be seen that whenever a fuse wire burns out the operator grasps the handle disk 33 and turns it so that either of the graduations thereon will register with the mark 35 which will mean that another wire 40 is thrown into the circuit in place of one burnt out. The metal strips 38 engaged by the contacts 50 complete the circuit through whichever fuse wire it is desired to use. When necessary to open the switch the stick 15 may conveniently be used and will avoid the necessity for the operator to stick his hand into the casing which might possibly result in a shock.

If preferred each side of the casing may be provided with a hole 51 covered with wire screen 52 to permit expulsion of the air within the casing in the event of blowing out of any of the fuses, the wire screen preventing explosion in case the device is used in a gas laden atmosphere.

From the foregoing description and a

study of the drawings it will be apparent that I have thus provided a simply constructed fuse box and cut out switch which has the advantage of incorporating a lightning arrester within itself and which has the great advantage of providing a plurality of fuse wires anyone of which may be used at will so that fuse replacement in the usual manner will be avoided.

While I have shown and described the preferred embodiment of the invention it is of course to be understood that I reserve the right to make such changes in the form, construction and arrangement of parts as will not depart from the spirit of the invention or the scope of the subjoined claim.

Having thus described my invention I claim:

In a replaceable fuse device, a casing, brackets mounted within the casing, a shaft journaled through said brackets, a cylinder of insulating material carried by said shaft and prevented from longitudinal displacement by engagement of its ends with the brackets, said cylinder having reduced end portions and being formed with a series of longitudinal grooves leading to said reduced end portions, metallic strips secured in spaced relation upon the reduced ends opposite said grooves and carrying binding screws, fuse wires located within the grooves with their ends secured by said screws, a stationary support, spring fingers carried by the support opposite the reduced ends of the cylinder and adapted to engage the successive metallic strips, and coil springs engaged beneath the ends of the spring fingers for urging them into engagement with the strips.

In testimony whereof I affix my signature.

ROY HENDERSON.
